US00D948213S

(12) **United States Design Patent** (10) **Patent No.:** **US D948,213 S**
(45) **Date of Patent:** **** Apr. 12, 2022**

(54) **CASE**(71) Applicant: **Apple Inc.**, Cupertino, CA (US)(72) Inventors: **Vijay Karthik Koneru**, Los Angeles, CA (US); **Christopher Wiita**, West Hollywood, CA (US); **Duy P. Le**, Los Angeles, CA (US); **Guillaume Raoult**, San Francisco, CA (US); **Elvin Chu**, San Francisco, CA (US); **Martin Gschwandtl**, San Francisco, CA (US); **Christopher Kuh**, San Francisco, CA (US); **Robert Brunner**, Glen Ellen, CA (US)(73) Assignee: **Apple Inc.**, Cupertino, CA (US)(**) Term: **15 Years**(21) Appl. No.: **29/762,027**(22) Filed: **Dec. 14, 2020****Related U.S. Application Data**

(63) Continuation of application No. 29/690,695, filed on May 9, 2019, now Pat. No. Des. 905,002, which is a continuation of application No. 29/685,004, filed on Mar. 25, 2019, now Pat. No. Des. 904,901.

(51) **LOC (13) Cl.** ..... **03-01**(52) **U.S. Cl.** ..... **D3/295****(58) Field of Classification Search**USPC D3/201, 218, 273, 274, 294, 295, 208,

CLAIM

The ornamental design for a case, as shown and described.

DESCRIPTION

FIG. 1 is a top front perspective view of a case showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the case that form no part of the claimed design.
